(57) **CLAIM**

The ornamental design for posture seat cushion, as shown and described.

DESCRIPTION

FIG. 1 is a front top perspective view of the posture seat cushion of the invention.

FIG. 2 is a top view of the posture seat cushion of FIG. 1. FIG. 3 is a front view of the posture seat cushion of FIG. 1, wherein the rear view and side views are identical; and, FIG. 4 is a bottom view of the handle plate of FIG. 1. The features inside the dashed lines boundary form no part of the design.
